The ornamental design for a medical/dental suction nozzle holster, as shown and described.

(57) **CLAIM****DESCRIPTION**

FIG. 1 is a perspective front view of a medical/dental suction nozzle holster showing our new design.

FIG. 2 is a perspective rear view of a medical/dental suction nozzle holster showing our new design.

FIG. 3 is a front elevational view thereof.

FIG. 4 is a right side elevational view thereof.

FIG. 5 is a rear elevational view thereof.

FIG. 6 is a top plan view thereof; and,

FIG. 7 is a bottom plan view thereof.
